DOOR OPERATING MECHANISM

Filed Nov. 6, 1944

2 Sheets-Sheet 2

At the forward end of the carriage 22 there is provided an upstanding lug or arm 36 which in the position shown in Figures 1, 2, and 3 is in engagement with the dependent extremity of a rod 38 suitably supported by guide members 40 and 42 secured to one side of the beam 16.

Adjacent the end of the rail 18 there is provided a latching member 44 having an actuating arm 46, a second actuating arm 48, a strike 50 and a hook 52 arranged at approximately equal angular intervals of the pivot of the member 44. The arm 46 may be provided with a cord 53 so that the member 44 may be actuated manually whenever desired. The hook 52 of the member 44 is adapted to engage the upstanding lug or arm 36 of the carriage 22 when the doors 10 and 12 have been moved outwardly.

The rod 38 at its other extremity is connected to a time delay mechanism 54 which may be in the form of a simple screen door check having a piston 56 and an energy storage coil spring 58. Any suitable type of energy storage means providing the proper time delay may be used in place of the mechanism shown in the drawing. At an intermediate point the rod 38 is provided with a collar 60 shown in greater detail in Figure 6. The collar 60 has two portions 62 and 64 for engagement with the arm 48 of the member 44 and with the latching portion of another arm mounted horizontally above the beam 16. A projecting portion 62 of the collar 60 which preferably is arranged so as to be adjustably positioned on the rod 38, is adapted to engage the arm 48. The other projecting portion 64 of the collar 60 is adapted to engage the hook 66 of an actuating member 68 pivotally supported on the top of the beam 16. The member 68 is provided with a strike 70 and with an actuating arm 72. The actuating arm 72 has a cord or rope 78 attached to the end thereof and the cord passes over a suitable pulley 80 positioned on the other side of the beam 16.

The members 28 and 30 shown in Figures 1 and 4 are disclosed with greater clarity in Figures 7 and 8 wherein only one member 28 has been shown. The ends of the member 28 are threaded and an eyelet 82 is formed at the apex of the angle between the two leg portions of the member 28. Each of the threaded portions 84 and 86 is mounted on the door in the manner shown in Figure 8 wherein the one leg of the member 28 is provided with a lock nut 88 and a cap nut 90 having a head adapted to engage the outer surface of the door 10. When the lock nut 88 is loose the head 90 may be adjusted so as to properly position the member 28 and its eyelet 82 relative to the arm 24 so that the mechanism will move the door 10 to its proper position in open or closed condition. When this adjustment has been obtained by the member 90, the lock nut 88 is tightened to retain the adjustment.

The operation of the mechanism will become apparent by assuming that the apparatus is in the condition shown in Figure 1 where the doors 10 and 12 are closed. In order to open the doors 10 and 12, it is necessary to push against one of the doors whereupon the carriage 22 will be moved forwardly along the rail 18 until the forward edge 92 of the carriage 22 as seen in Figure 6 engages the strike 50 of the member 44 so as to cause the hook 52 to be moved in back of the upstanding lug 36 on the carriage 22. The hook 52 of the member 44 therefore retains the spring or energy storage member in extended condition until released. If it is desired to have the doors

close immediately it is only necessary to grasp the rope 53 and to pull downwardly on the lever 46 so as to raise the catch 52 to permit the upstanding lug 36 of the carriage 22 to escape so that the carriage 22 will be drawn rearwardly by the energy stored in the spring 34. The doors 10 and 12 thereupon will again be closed as shown in Figure 1.

It may now, however, be assumed that the doors 10 and 12 have been opened and that the hook 52 of the member 44 is retaining by engagement with the member 36 the carriage 22 in its forward position. The automobile owner thereupon may enter the automobile and start the motor. Just prior to shifting gears and engaging the clutch, the operator may reach outside of the car and grasp the rope 78 to pull upon the lever 72 which will disengage the hook 66 from the upstanding lug 64 on the collar 60 which is mounted on the rod 38. As is apparent from Figure 2 the rod 38 has been moved rearwardly at the time that the carriage 22 was at its rear position so that the collar 60 is retained by the member 68. When, however, the lever 72 is actuated, the member 68 releases the collar 60 thus permitting the spring 58 of the door check 54 to release its energy and to move the rod 38 forwardly along the beam 16. The collar 60 therefore moves forwardly until it engages the lever 48. In Figure 4 the collar 60 is shown midway between the members 68 and 44 which condition occurs during the time interval required for the door check to move its piston 56 to its normal limit. While the member 60 is moving, the automobile driver drives out of the garage and leaves. Shortly thereafter the member 60 is moved to a position where the arm 62 thereof engages the lever 48 so as to bring about the disengagement of the hook 52 from the upstanding lug portion 36 of the carriage 22. This permits the spring 34 to return the carriage 22 to the position shown in Figures 1 and 2. At the time when the carriage 22 is reaching its rearmost limit of travel, the upstanding lug 36 engages the depending end of the rod 38 so as to again compress the spring 58 of the door check 54. The movement of the rod 38 by the carriage 22 causes the collar 60 to engage the strike 70 of the member 68 so as to bring the hook 66 in such position that even though the collar 60 moves slightly beyond the position shown in Figure 3, the hook 66 will prevent movement of the collar 60 forwardly of the position shown in Figure 3. The time delay device comprising the door check 54, the operation of which is adjustable by virtue of the customary adjustment means 55, therefore serves to determine the time interval between the initiation of the releasing action by actuation of the lever 72 and the time when the carriage 22 actually is released. The door check 54 also serves to cushion and retard in a decelerating manner the final portion of the movement of the carriage 22 thereby reducing and substantially obviating shock upon the doors 10 and 12 at the time when they are substantially in closed position.

From the foregoing explanation it will readily be appreciated that while for the convenience of illustration, the rope 78 has been shown in passing over but a single pulley 80, additional pulleys may be provided so as to bring this rope to the desired position in the garage adjacent the driver's side of the automobile or vehicle stored within the garage.

75 While it has been convenient for the purpose

of disclosing the present invention to show the application of the invention to a dual door arrangement, it will readily be appreciated that the invention is readily applicable to other types of door structures such as for example an overhead door. The application of the present invention to such structures does not change the principle of operation and involves merely slight re-arrangement of the location of the assembly and possibly a modification of the link interconnecting the carriage with the door. It therefore is readily apparent to those skilled in the art that the invention is susceptible of application to other types of door structures.

It furthermore will be appreciated that while a preferred embodiment has been shown in the drawings that the invention is not to be limited thereby since obviously variations may be made in the configuration of the components employed and in their location without departing from the spirit and scope of the invention as set forth in the appended claims.

This invention is hereby claimed as follows:

1. A mechanism for a door comprising a rail arranged perpendicular to the plane of the frame of the door in closed position, a carriage slidably mounted on said rail, an arm interconnecting said carriage and said door, energy storage means for urging said carriage to a predetermined position whereby the door will be in the closed position, latching means arranged adjacent said rail and adapted to engage and retain said carriage when said door is opened, manual means to unlatch said latching means whereby said energy storage means moves said carriage and said doors to the closed position without delay, a time delay mechanism including a movable arm, said arm engaging said carriage upon movement of said carriage to said predetermined position whereby to energize said time delay mechanism, holding means effective to retain said arm in the energized position, means to release said arm from said holding means whereby said arm is moved by said time delay mechanism to unlatch said latching means after a predetermined time interval.

2. A mechanism for a door comprising a rail arranged perpendicular to the plane of the frame of the door in closed position, a carriage slidably mounted on said rail, an arm interconnecting said carriage and said door, a spring connected between a fixed point and said carriage for urging said carriage to a predetermined position whereby the door will be in the closed position, latching means arranged adjacent said rail and adapted to engage and retain said carriage when said door is opened, a time delay mechanism including a movable arm, said arm engaging said carriage upon movement of said carriage to said predetermined position whereby to energize said time delay mechanism, holding means effective to retain said arm in the energized position, means to release said arm from said holding means whereby said arm is moved by said time delay mech-

anism to unlatch said latching means after a predetermined time interval.

3. A mechanism for dual doors in a building comprising a rail positioned perpendicular to the plane of the closed doors, a carriage slidably mounted on said rail, arms interconnecting said carriage and said doors, a spring connected between a fixed point and said carriage biasing said doors toward a closed position, latching means arranged adjacent said rail and adapted to engage and retain said carriage when said doors are opened, manual means to unlatch said latching means to permit said spring to move said carriage and said doors to the closed position without delay, a time delay mechanism including a movable arm, said arm engaging said carriage upon movement of said carriage to the closed position whereby to energize said time delay mechanism, holding means effective to retain said arm in the energized position, means to release said arm from said holding means whereby said arm is moved by said time delay mechanism to unlatch said latching means after a predetermined time interval.
4. A mechanism for dual doors in a building comprising a rail positioned perpendicular to the plane of the closed doors, a carriage slidably mounted on said rail, arms interconnecting said carriage and said doors, a spring connected between a fixed point and said carriage biasing said carriage and said doors toward a closed position, latching means arranged adjacent said rail and adapted to engage and retain said carriage when said doors are opened, manual means to unlatch said latching means to permit said spring to move said carriage and said doors to the closed position without delay, a time delay mechanism including a movable arm, said arm engaging said carriage upon movement of said carriage to the closed position after each time said time delay mechanism operates whereby to energize said time delay mechanism, holding means effective to retain said arm in the energized position, means to release said arm from said holding means whereby said arm is moved by said time delay mechanism to unlatch said latching means after a predetermined time interval.
